GAS STORAGE CONTAINER

William T. Hudson, Houston, Tex., assignor to
Chicago Bridge & Iron Company, a corporation
of Illinois

Application January 5, 1946, Serial No. 639,440

13 Claims. (Cl. 48—178)

1
This invention relates to a gas storage container for the storage of gas under pressure.

It is common practice when storing volatile liquids to provide additional storage space for the gases evolved from the liquid. In the ordinary installation this is done by having an expansible balloon communicating with the storage tank for the volatile liquid. As the gases are evolved they flow into the balloon where they are stored under pressure. When condensation occurs or when the gases are withdrawn for use the expansible balloon collapses. It is preferred that the gas be stored under substantially constant pressure, but this is not always true in the ordinary balloons.

I have invented a gas storage balloon comprising a hollow shell that is preferably located around the shell of a storage tank. The hollow shell is provided with flexible sealing means dividing the hollow shell into sections that are movable toward and away from each other and toward and away from the tank shell. Hanger means are mounted on the tank shell for movably supporting the sections, and a gas flow conduit is provided communicating with the space between the hollow shell and the tank shell. Thus the balloon will have an annular storage space whose inner wall is fixed, but whose outer wall is movable.

The invention will be described as related to the embodiment shown in the accompanying drawings. Of the drawings Fig. 1 is a plan view of a gas storage balloon embodying the invention with portions broken away for clarity of illustration; and Fig. 2 is a vertical section substantially through the center of the balloon of Fig. 1.

The gas storage balloon shown in the accompanying drawings comprises a center cylindrical shell 10 which may be the shell of a storage tank, an outer cylindrical shell 11 made up of sections 12 of a cylinder, and hanger bars 13 extending between the inner cylinder 10 and the outer cylindrical sections 12 movably supporting said sections.

Between adjacent vertical edges of the cylindrical sections 12 there are located flexible sealing members 14 that render these areas gas-tight. Reinforcements such as chains 15 are provided in order to reinforce the sealing members 14 and remove tension from them.

The hanger bars 13 are rotatably mounted on the inner cylinder 10 and at each cylindrical section 12 by means of brackets 16. As shown there are four hanger bars to each cylindrical section 12 with one pair being at the top and the

2
other at the bottom. These hanger bars permit movement of the cylindrical sections 12 toward and away from the inner cylinder 10 and toward and away from each other. It is preferred that the hanger bars be inclined upwardly from the inner cylinder 10 so that the weight of the cylindrical sections 12 always tends to hold them against the inner cylinder 10. Under these conditions the gas will be stored at substantially constant pressure at all times.

The gas storage balloon of this invention may be used around the shell of a storage tank having either a fixed roof or a floating roof. In the embodiment shown the inner cylinder 10 is the shell of a floating roof tank with the floating roof not shown.

An annular wind girder 17 is provided at the top of the inner cylinder 10, projecting beyond the farthest position of the cylindrical sections 12. This wind girder has a downwardly projecting portion 18 at its outer edge, and the girder serves to protect the top of the storage balloon from wind, rain, snow, and the like. A gas conduit 19 is provided for flow of gas into the storage portion of the balloon with the conduit extending through the annular wind girder 17.

In order to seal the bottom area between the inner cylinder 10 and cylindrical sections 12 there is provided an annular flexible sealing member 20 extending between the bottom edges of the cylindrical sections 12 and the bottom edge of the inner cylinder 10. The inner edge of the flexible sealing member 20 may be attached to an extension 21 of the tank bottom 22. There is also a similar annular sealing member 23 provided at the top of the cylindrical sections 12 with the inner edge of this sealing member fastened to the wind girder 17 beyond the gas conduit 19.

In order to limit outward movement of the cylindrical sections 12 to provide a gas storage space having a predetermined maximum, there is provided an ordinary release valve 24 mounted on one of the cylindrical sections 12 and connected to the inner cylinder 10 by a flexible member such as a chain 25. As soon as the cylindrical sections 12 have reached their predetermined maximum movement as shown in Figs. 1 and 2, the chain 25 causes a valve 24 to open and vent the excess gases.

The flexible sealing members 14 between adjacent vertical edges of the cylindrical sections 12 and the top and bottom sealing members 20 and 23 are preferably fabric impregnated with a flexible gas impervious material.

Although the inner cylinder 10 is shown as part

of a floating roof tank, the balloon may be used on any kind of tank desired. Where the tank is one having a fixed roof the wind girder 17 may be only an overhanging extension of the fixed roof.

A gas storage balloon of the type shown and described herein not only serves to store gas under pressure, but also performs a secondary service in insulating the tank around which it is built. This insulating effect would serve to reduce evaporation of the contents of the inner cylinder 10 caused by the heat of the sun.

When the gas storage balloon is empty the cylindrical sections 12 will be adjacent the inner cylinder 10. As gas flows through the conduit 19, which may be connected to storage tanks of fixed capacity, the sections 12 move away from the inner cylinder 10 until the maximum capacity has been reached. At this point the chain 25 will vent excess gas through the valve 24.

Having described my invention as related to the embodiment shown in the accompanying drawings, it is my intention that the invention be not limited by the details of description unless otherwise specified, but rather be construed broadly within its spirit and scope as set out in the accompanying claims.

I claim:

1. A gas storage container comprising a hollow shell to be located around the shell of a storage tank, flexible sealing means dividing said hollow shell into gas tight sections that are movable toward and away from each other and toward and away from the tank shell in a substantially horizontal plane, hanger means to be mounted on the tank shell for movably supporting the sections, and a gas flow conduit communicating with the space between the hollow shell and the tank shell.

2. The container of claim 1 wherein means are provided tending to hold the hollow shell adjacent the tank shell.

3. The container of claim 1 wherein the tank shell is substantially a cylinder and the hollow shell comprises substantially cylindrical sections.

4. The container of claim 1 wherein the hanger means are pivotally attached to the tank shell and the hollow shell and are pivotal at the tank about an axis slightly inclined from the vertical, said hangers being inclined upwardly from the tank to the hollow shell so that the weight of the sections tends to hold them adjacent the tank shell.

5. A gas storage container comprising a hollow shell to be located around the shell of a substantially cylindrical storage tank with the hollow shell comprising sections of cylinders having their vertical edges adjacent each other and with flexible sealing means connecting said adjacent edges, hanger means to be mounted on the tank shell for movably supporting the sections with said sections being movable toward and away from each other and toward and away from the tank shell in a substantially horizontal plane, gas flow conduit means communicating with the space between the hollow shell and the tank shell, sealing means sealing the area between the bottom of the hollow shell and the tank shell, and sealing means sealing the area between the top of

the hollow shell and the tank shell to form a gas tight hollow shell about the tank shell.

6. The container of claim 5 wherein said sealing means connecting adjacent edges of the cylindrical sections and the sealing means at the bottom and top of the hollow shell are flexible sealing members that permit movement of the cylindrical sections.

7. The container of claim 5 wherein flexible reinforcements are provided at the adjacent edges of the cylindrical sections to reinforce the sealing means at said edges.

8. The container of claim 5 wherein flexible reinforcements comprising chains are provided at the adjacent edges of the cylindrical sections to reinforce the sealing means.

9. The container of claim 5 wherein means are provided limiting outward movement of said hollow shell to a predetermined maximum.

10. The container of claim 5 wherein means are provided limiting outward movement of said hollow shell to a predetermined maximum, said means comprising a flexible member attached to the tank shell and connected to a valve means mounted on one cylindrical section.

11. The container of claim 5 wherein the hanger means are pivotally attached to the tank and to the hollow shell and are pivotal at the tank about an axis slightly inclined from the vertical, said hanger means being inclined upwardly from the tank shell to the hollow shell so that the weight of the cylindrical sections tends to hold them adjacent the tank shell.

12. A gas storage container comprising a hollow shell to be located around the shell of a substantially cylindrical storage tank with the hollow shell comprising cylindrical sections having their vertical edges adjacent each other and with flexible sealing members and spaced chains connecting said adjacent edges, hanger means comprising bars to be pivotally attached to the tank shell and the cylindrical sections, said bars being pivotal at the tank about an axis slightly inclined from the vertical and with each bar inclined upwardly from the tank shell so that the weight of the sections tends to hold them against the shell, flexible sealing members sealing the area between the bottom of the hollow shell and the tank shell, flexible sealing members sealing the area between the top of the hollow shell and the tank shell, and gas flow conduit means communicating with the space between the hollow shell and the tank shell.

13. A gas storage container having an annular storage space and comprising an inner cylindrical shell and a movable outer cylindrical shell, said outer shell comprising cylindrical sections having their vertical edges joined by flexible sealing means with each section being supported for movement toward and away from each other and toward and away from the inner cylindrical shell in a substantially horizontal plane, and flexible sealing means sealing the space at the top of the outer shell and at the bottom of the outer shell.
